UNITED STATES PATENT OFFICE.

JAMES F. PLACE, OF GLENRIDGE, NEW JERSEY.

VESSEL FOR HOLDING AND SHIPPING LIQUID AIR OR OTHER LIQUID GASES.

SPECIFICATION forming part of Letters Patent No. 707,634, dated August 26, 1902.

Application filed February 10, 1902. Serial No. 93,289. (No model.)

To all whom it may concern:

Be it known that I, JAMES F. PLACE, a citizen of the United States, and a resident of Glenridge, in the county of Essex and State of New Jersey, have invented certain new and useful Improvements in Vessels for Holding and Shipping Liquid Air or other Liquid Gases, of which the following is a specification.

This invention relates to vessels, either portable or stationary, bottles, or receptacles for holding, carrying, or storing liquid air or other liquefied gases or substances of any kind which it is desirable to insulate from heat or cold.

15 The object of the invention is to provide means for holding, storing, or shipping such liquefied air or other liquid gases, and especially to thoroughly insulate and preserve the same or any other matter while being stored or carried from place to place from the normal heat of the atmosphere or from the heat of the room where stored, kept, or placed or of the compartment of the car or other room when *in transitu*.

25 A further object is to provide a convenient receptacle for holding such liquid gases while the same are in use, so that said liquid air or other liquid gases may be drawn from the container, receptacle, or bottle as desired, 30 either in part or whole, and if drawn in part that the remaining portions will still continue to be insulated and may be retained.

A further object is to provide such a bottle, receptacle, or container so that the liquid 35 air or other liquefied gas therein may be kept under tension from slight evaporation and may be drawn, forced, or siphoned out by such tension or may be used at atmospheric pressure, and so that any vapor from such 40 liquid may be allowed to escape at atmospheric pressure or may be availed of at such pressure or tension as may be desired.

A still further object is to cheapen the cost 45 of construction of such receptacles, bottles, or containers, and yet to still retain their highest possible efficiency for retaining and preserving such liquefied air or other liquid gases in a liquid form.

These objects are accomplished in the manner 50 and by the means hereinafter described and claimed, reference being made to the accompanying drawings, in which—

Figure 1 is a vertical section of a vessel, bottle, receptacle, or container for such liquefied air or other liquid gases constructed in 55 accordance with my invention. Fig. 2 is a horizontal section of same on the line *x x* of Fig. 1 looking upward toward the top. Fig. 3 is a plan view of the delivery-tube or siphon vapor delivery or vent tube, with 60 their valves or cocks, sight pressure-gage, &c. Fig. 4 is a side elevation of same looking toward the edge of pressure-gage. Fig. 5 is a modification in vertical section of the construction of the inner bottle, showing 65 how a screw-stopper may be used so as to withstand a pressure in said bottle and also showing how the air-tight covering of the outer case and lining of the inner bottle may be made in separate parts and yet the whole 70 forming one complete air-tight inclosure. Fig. 6 is a vertical section of a modification in construction, on a small scale, of the top part of the receptacle, showing how the inner bottle can be used for holding and protecting 75 from heat solid substances—such, for instance, as frozen or solidified carbon dioxid or other like substances. Fig. 7 is a view in vertical section of another modification in construction of the lining of the inner bottle and the 80 sack or covering of the outer case, showing how same may be made in two separate parts and yet be conveniently fastened together so as to form one complete air-tight inclosure.

Similar reference-marks refer to similar 85 parts throughout the several drawings.

The numeral 1 (see Figs. 1 and 5) refers to the inner bottle or the liquid-holding receptacle, holder, or container, 1' being the walls or body of same, which I make of wood, 90 fiber, or some other material of relatively low heat conductivity and strengthen against bursting by the metal hoops 2. At 3 I show an outer case inclosing or surrounding said inner liquid-holding bottle and which I also 95 make of wood, indurated or other fiber, or other material of relatively low heat conductivity, the same being made sufficiently strong to withstand a collapsible pressure of fifteen pounds or more to the square inch. The top 100 and bottom of this outer case I make of similar suitable material and put together, as shown, or in any suitable manner, so as to withstand such collapsible pressure. The

top 4 has a hole in it for the neck of the inner liquid-holding bottle and on which the inner bottle hangs, as it were, or is fixed within said outer case, resting on or being supported by the top 4 by the projection or ring 5, which is fixed to the neck of the inner bottle, as shown. Any other suitable manner of supporting the inner bottle inside the outer case 3 will answer; but the manner shown and described is the preferred construction.

At 6 (see Figs. 1 and 2) I have three or more guide-pieces of cork, fiber, or any other suitable material of low heat conductivity to hold the inner bottle erect or rigidly inside the outer case 3 and prevent the same from swaying or swinging laterally. At 7 I provide a vacuum-chamber or vacuum-space, commonly called a "vacuum-jacket," between said outer case 3 and said liquid-holding bottle 1. Said vacuum chamber or space practically surrounds or incloses said inner liquid-holding bottle and forms an insulating vacuum-jacket for said inner bottle, and a vacuum being the best possible insulator against heat or almost a perfect non-conductor therefor said inner liquid-holding bottle and its contents or the liquefied air or other liquid gas contained therein is thus thoroughly insulated from the heat of the atmosphere or air in the room or compartment where it may be located. I do not attempt to make the walls 1' of the inner bottle 1 nor the outer case 3 impervious or air-tight; but at 8 (see Figs. 1, 2, and 5) I have an air-tight covering, sack, or impervious inclosure, which surrounds or incloses the outer case 3, and it passes inwardly over the outside of the ring-top 4 and over the ring projection 5 on the inner bottle 1 and also over the top edge or rim of the neck of said inner bottle, and enfolding within itself it passes down inside the neck into said inner bottle 1 and forms therein an inside impervious lining thereto at 8' and 8", thus substantially forming as a whole or being in shape of a cul-de-sac. This air-tight covering or inclosure I make of any suitable material, such as sheet German silver or sheet-lead, or any other suitable impervious material of relatively low heat conductivity. It will be seen that by making it so that it serves as an impervious inclosure, sack, or bag for the outer case 3 and also as an impervious lining for the inside of the inner bottle 1 in form of a bag or sack self-contained and without a hole or rupture at any point and with one part enfolded within the other part in form of a cul-de-sac the vacuum space or chamber 7 between the folds and around and under the inner bottle 1 and between that and the outer case 3 is made a perfectly air-tight space.

At 9 I have a passage through the covering 8 and through the bottom of the outer case 3 fitted with a valve, and after the air is pumped out of the chamber 7 I seal this passage air-tight by the cap 10.

At 11, for purposes of insulation, I have a thin packing of blotting-paper or wool felt-ing or some other suitable material of relatively low heat conductivity under the air-tight covering or inclosure 8 around, under, and over the outer case, and also at 11' under the enfolded part (8' and 8") of said covering, which acts as a lining inside the inner or liquid-holding bottle. At 12 I have packings of hair, felt, or any other suitable material of relatively low heat conductivity, which inclose or surround the whole in order to further insulate the same and the contents of said inner bottle from the heat of the outside atmosphere, which insulations are inclosed also by the outside protecting case, drum, or can 13, which may be made of wood or any other suitable material.

At 14 I have a siphon-tube which runs through the stopper or cap 15 of the inner bottle down to near the bottom of said inner bottle and connects through the cock 16 with the delivery-tube 17. This tube 14 passes through the larger tube 18, which opens into the top part of and inside the inner bottle, and whose outlet is through the cock 19 and the relief-valve 20 to the atmosphere outside. A sight-pressure gage 21 is connected with the larger tube 18 through the cock 22, thus showing at a glance the pressure in the inner bottle. If it is desired that the liquefied gas shall be kept under pressure or tension, the same can be obtained by setting the relief-valve 20 so that it will open only at such predetermined pressure as required or which can be allowed with safety, and closing the cock 16. By unscrewing the part containing the cocks, delivery-tube, gage, &c., at 23 the same can be removed from the larger tube 18 and lifted off with the siphon-tube 14, when the cover 13' of the protecting-case 13 can be taken off and the stopper 15 of the inner liquid-holding bottle be removed, and with it also the larger tube 18. In this way the inner bottle can be readily refilled with the liquefied air or other liquid gas. Where the liquid is to be kept or retained under pressure or tension, this stopper 15 can be screwed into the neck of the liquid-holding bottle on the screw-threads in said neck. (Shown in Fig. 5.) In that case the enfolding part of the lining 8' can be passed outwardly over the shoulders of the neck of the inner bottle, as at 24 and 24', in the modification of construction shown in Fig. 5. In this way the pressure inside on the stopper 15 will not disturb the lining. At 15' (see Fig. 1) I have a form of insulation in this stopper 15 in shape of paper or fiber rings or disks to form dead-air spaces in the stopper between said disk 15'. I do not confine myself to this way of holding in the stopper. Any other suitable way or any other style of stopper will answer as well; nor do I confine myself to the shape and arrangement of siphon, vent, and delivery tubes, as shown. Any other suitable arrangement will answer as well. The pre-

ferred construction, however, is as shown, and the tubes, connections, and stoppers should be made of suitable materials of relatively low heat conductivity—such, for instance, as wood, fiber, hard-pressed paper, or some like material.

I do not confine myself to any special or particular shape of either the liquid-holding bottle or of the outer case or of the protecting-case. Either round, square, hexagon, or other shape will do and the same may be long or short. The preferred construction, however, is, as shown, round. The neck of the inner liquid-holding bottle I prefer should be rather long, so that any heat which may be conducted down the neck or lining 8' thereof may have a greater distance to travel before reaching the liquid contents within the bottle. The air-tight or impervious covering 8 and lining 8' and 8'' should be quite thin, so as to have the sectional area of conductivity, especially where it serves as a lining for the neck of the inner bottle, as small as possible, yet it must be sufficiently thick to insure a perfectly air-tight inclosure. The outside of the covering 8 I nickel or silver plate, so as to give as glossy a polish as possible, and the outside of the enfolding part of said covering, which forms the lining of the inner bottle, is similarly treated in order to prevent as much as possible the passage of heat by radiation. In this respect I do not confine myself to plating or to plating any particular part, but prefer to polish such parts or sides and in such a manner as will best serve the purpose desired. The preferred construction of the covering 8 and its enfolded part or lining 8' and 8'' is to make in sections and solder the edges of the same together or otherwise make fast and air-tight after it is all together and in place, as shown in Fig. 1. In the modification shown in Fig. 5, however, the air-tight covering or impervious inclosure around the outer case 3 is a separate covering distinct from the lining for the inner bottle, as shown at 25, where the mouth or edge of the sack is shown. At 26 the mouth or neck of the lining of the inner bottle ends. In that case the impervious lining of the inner bottle at or near the neck or mouth of same or edge of the opening is soldered or otherwise made fast and air-tight to the ring 5', which can be made of metal, if this form of construction is adopted; or the covering or sack for the outer case may have its mouth as shown at 27, Fig. 7, and the mouth or neck of lining may end at 28 and both edges be lapped over and soldered or otherwise made fast and air-tight to the metal hoop 29. In this way the lining of the inner bottle, although distinct from the covering or sack over the outer case, may be soldered or otherwise made fast to the mouth of said covering, and so as to leave the mouth or neck of the inner bottle lining open, and so as to close the mouth of said outer case covering or sack, thus forming around said outer case and the inner bot-

tle therein one complete air-tight inclosure. These modifications, however, are equivalents of the preferred construction shown in Figs. 1 and 2, as the metal hoop or ring 29 and the supporting-ring 5' when made of metal and used as described in either case form a part of the self-contained covering or inclosure and its enfolded part, which forms the lining to the inner liquid-holding bottle. I do not confine myself to these details of construction as to this outer-case covering and inner-bottle lining. The essential object sought is to provide a vacuum-jacket for the inner bottle and secure it air-tight and to do this by the use of materials of low heat conductivity, to reduce to the minimum the conduction or radiation of heat to the contents of the inner bottle, and to construct at small cost a vessel or receptacle which will not only retain or carry the liquefied air or gas with the least possible evaporation, but will be both light in weight and convenient for use, and which can be built in such sizes as required and used either as a stationary or portable vessel or container or as a shipping-receptacle.

Liquid air and most other liquefied gases are at a temperature much below that of the atmosphere, and consequently they are in a constant state of ebullition or evaporation. In most cases bottles or receptacles for holding, shipping, or storing the same are necessarily made of copper or galvanized steel in order to secure sufficient strength, and the insulation of such receptacles is largely counteracted and lost by reason of the high heat conductivity of such metals. Even when a vacuum-jacket is used in accordance with my United States Patent No. 646,459 the amount and thickness of metal required to give rigidity to the outer case and necessary strength to the inner bottle in order to withstand the pressure or tendency to collapse caused by the vacuum are such that the area of conduction and high degree of conductivity allow the heat to pass down the relatively large sectional area of metal in and around the neck of the inner bottle more rapidly and in greater quantity than should be allowed, and thus the great value of the vacuum as an insulator is in the main largely counteracted.

By constructing a bottle or receptacle for holding, shipping, or storing liquid air or other liquefied gases in accordance with my present invention, as herein described, the frame or body of both the inner liquid-holding bottle and the outer case can be made of wood or even of porous fiber or any other similar and suitable material that will supply and maintain that rigidity necessary to withstand either the collapsible or bursting pressure caused by the vacuum outside or the tension inside the inner bottle, and both the lining in the inner bottle and the covering over the outer case can be then made of thin fine-grained sheet metal or other similar material, and thus the vacuum-jacket inclosure

will be maintained perfectly air-tight, and at same time the sectional area of conduction is small and its heat-conductivity will be relatively low, so that the amount of heat passing down into the inner bottle will be necessarily limited or reduced to the minimum.

In Fig. 6 I show how the inner bottle can be made so as to hold solid substances—such, for instance, as frozen or solidified carbon dioxide or other solidified substances, which require in order to be retained in solid form to be thoroughly insulated from the heat of the atmosphere. In such cases I make the neck of the inner bottle of substantially the same size or diameter as the lower body, as shown at 31 in Fig. 6, and I have a removable inner receptacle 32, which can be slipped into the inner bottle 1, as shown. This removable receptacle 32 may be made of wood or fiber and lined with some sheet metal of low heat conductivity, as at 33, Fig. 6, which lining need not come to the top of the receptacle. At 34 I have a cap screwed in, as at 35, which cap is insulated by dead-air spaces 36. The removable receptacle 32 can be quickly removed, and the cap may also be removed for filling the removable receptacle 32. At 37 I have a small vent through the cap, closed by a rubber or leather flap check-valve, the partitions 36' not being fitted air-tight. This flap-valve is for the purpose of giving vent to the contents of the receptacle in such cases as when it is not desired that the vapor given off by such contents shall generate a tension or pressure in the receptacle. In such cases when pressure is not desired to any considerable tension the stopper may be made in the ordinary manner of cork or fiber and pressed into the mouth of the removable receptacle or inner bottle, as shown in Fig. 1, instead of being screwed in.

Having thus described my invention, what I claim as new and original, and desire to secure by Letters Patent, is—

45 1. In a receptacle or container for liquid air or other liquefied gas, comprising an inner liquid-holding bottle or vessel and an outer case; an air-tight covering or impervious inclosure inclosing said receptacle, one part of which is infolded within itself in form of a cul-de-sac, and which serves as a lining to the inner liquid-holding bottle, and the other part or fold of which incloses a vacuum jacket or chamber around said liquid-holding bottle or vessel, substantially as shown and described.

60 2. In a receptacle or container for liquid air or other liquefied gas, comprising an inner liquid-holding bottle and an outer case; an inside impervious lining within said inner bottle, and an impervious covering over the outside of and inclosing said outer case—said lining and said covering being closed or soldered together so as to form an air-tight inclosure, substantially as shown and described.

65 3. In a receptacle or container for liquid air or other liquefied gas, comprising an in-

ner liquid-holding bottle and an outer case; an inside impervious lining within said inner bottle, and a sack or impervious covering over the outside of and inclosing said outer case—said lining at or near the neck of same being soldered or made fast and air-tight to the mouth of said covering or sack, so as to leave the mouth or neck of said lining open, and so as to close the mouth of the outer-case covering or sack, thus forming around said outer case an air-tight inclosure, substantially as shown and described.

4. In a receptacle or container for liquid air or other liquefied gas, comprising an inner liquid-holding bottle and an outer case; the combination of an inside lining within said inner bottle, and a covering over the outside of and inclosing said outer case—said lining and said covering being impervious and closed or soldered together so as to form an air-tight inclosure; and a vacuum chamber or space between the said inside lining within said liquid-holding bottle and the said air-tight covering or inclosure around the said outer case, substantially as shown and described.

5. In a receptacle or container for liquid air or other liquefied gas, comprising an inner liquid-holding bottle and an outer case; the combination of an inside impervious lining within said inner bottle and a sack or impervious covering over the outside of and inclosing said outer case—said lining at or near the neck of same being soldered or made fast and air-tight to the mouth of said covering or sack, so as to leave the mouth or neck of said lining open, and so as to close the mouth of the outer-case covering or sack, thus forming around said outer case an air-tight inclosure; and a vacuum chamber or space between the said inside impervious lining within said liquid-holding bottle and the said air-tight covering or inclosure around the said outer case, substantially as shown and described.

6. In a receptacle or container for liquid air or other liquefied gas, the combination of an inner bottle or liquid-holder inclosed in or surrounded by an outer case; with a vacuum chamber or space between said inner bottle and said outer case; and an air-tight covering of suitable material inclosing said outer case, and infolding over the rim of the neck or mouth of and passing down into said inner bottle as an inside lining thereto, in form of a cul-de-sac, substantially as shown and described.

7. In a receptacle or container for liquid air or other liquefied gas, the combination of an inner liquid-holding bottle inclosed in or surrounded by an outer case, both said inner bottle and said outer case being made of wood or fiber or some other material of relatively low heat conductivity; with an air-tight covering or impervious inclosure which incloses said outer case, and infolds within itself or passes down into said inner liquid-holding

bottle as an inside impervious lining thereto; and a vacuum chamber or space between said inclosed outer case and said inner liquid-holding bottle, substantially as shown and described.

8. In a receptacle or container for liquid air or other liquefied gas, the combination of an inner liquid-holding bottle inclosed in or surrounded by an outer case, both said inner bottle and said outer case being made of wood or fiber or other suitable material of relatively low heat conductivity; with an air-tight covering or impervious inclosure of sheet metal or other suitable material, which incloses said outer case and infolds within itself or passes down into said inner liquid-holding bottle as an inside impervious lining thereto; and a vacuum chamber or space between said inclosed outer case and said inner liquid-holding bottle, substantially as shown and described.

9. In a receptacle or container for liquid air or other liquefied gas, the combination of an inner bottle or liquid-holder inclosed in or surrounded by an outer case; with a vacuum chamber or space between said inner bottle and said outer case; and an air-tight covering of suitable material inclosing said outer case, and infolding over the rim of the neck or mouth of and passing down into said inner bottle as an inside impervious lining thereto, in form of a cul-de-sac, the whole being insulated from the heat of the outside atmosphere by packings of hair felt or other material of relatively low heat conductivity, and inclosed in an outside protecting-case, substantially as shown and described.

10. In a receptacle or container for liquid air or other liquefied gas, the combination of an inner liquid-holding bottle inclosed in or surrounded by an outer case, both said inner bottle and said outer case being made of wood or fiber or some other material of relatively low heat conductivity; with an air-tight covering or impervious inclosure which incloses said outer case, and infolds within itself or passes down into said inner liquid-holding bottle as an inside impervious lining thereto; and a vacuum chamber or space between said inclosed outer case and said inner liquid-holding bottle, the whole being insulated from the heat of the outside atmosphere by packings of hair felt or other material of relatively low heat conductivity, and inclosed in an outside protecting-case, substantially as shown and described.

11. In a receptacle or container for liquid air or other liquefied gas, the combination of an inner liquid-holding bottle inclosed in or surrounded by an outer case, both said inner bottle and said outer case being made of wood or fiber or other suitable material of relatively low heat conductivity; with an air-tight covering or impervious inclosure of sheet metal or other suitable material, which incloses said outer case and infolds within itself or passes down into said inner liquid-holding bottle as

an inside impervious lining thereto; and a vacuum chamber or space between said inclosed outer case and said inner liquid-holding bottle, the whole being insulated from the heat of the outside atmosphere by packings of hair felt or other material of relatively low heat conductivity, and inclosed in an outside protecting-case, substantially as shown and described.

12. In a receptacle or container for solidified carbon dioxid or other solid substances which require to be insulated from the heat of the atmosphere, the combination of an inner bottle or receptacle, and an outer case; with an air-tight covering or impervious inclosure which incloses said outer case, and infolds within itself or passes down into said inner bottle as an inside air-tight lining thereto; and a vacuum chamber or space between said air-tight-covered outer case and said air-tight-lined bottle, substantially as shown and described.

13. In a receptacle or container for solidified carbon dioxid or other solid substances which require to be insulated from the heat of the atmosphere, the combination of an inner bottle or receptacle and an outer case; with an air-tight covering or impervious inclosure which incloses said outer case, and infolds within itself or passes down into said inner bottle as an inside air-tight lining thereto; and a vacuum chamber or space between said air-tight-covered outer case and said air-tight-lined inner bottle, and a removable receptacle adapted to slip into said air-tight-lined inner bottle, substantially as shown and described.

14. In a receptacle or container for solidified carbon dioxid or other solid substances which require to be insulated from the heat of the atmosphere the combination of an inner bottle or receptacle and an outer case; an inside impervious lining within said inner bottle, and an impervious covering over the outside of and inclosing said outer case—said lining and said covering being closed or soldered together so as to form an air-tight inclosure; and a removable substance-holding receptacle adapted to slip into said air-tight-lined inner bottle, substantially as shown and described.

15. In an insulated receptacle or container for liquid air or other liquefied gas, the combination of an inner liquid-holding bottle or vessel; with an outer receptacle inclosing said inner bottle; and an air-tight sack or covering inclosing said outer receptacle, one part of which covering is infolded within itself in form of a cul-de-sac, and which serves as an inside lining to the inner liquid-holding bottle, substantially as shown and described.

16. In a receptacle or container for insulating and preserving liquid air or other matter against the normal heat of the atmosphere, the combination of an outer receptacle inclosed by an air-tight sack or covering; with an inner bottle or vessel fixed within said outer receptacle, and having an air-tight in-

6
side lining—said covering and said lining forming one complete inclosure; and a vacuum jacket or space around said inner bottle between the lining thereof and the air-tight 5 sack or covering of said outer receptacle, substantially as shown and described.

17. In a receptacle or container for insulating and preserving liquid air or other matter against the heat of surrounding atmosphere, 10 the combination of an outer receptacle inclosed by an air-tight sack or covering; with an inner bottle or vessel fixed within said outer receptacle, and having an air-tight inside lining—said covering and said lining forming one 15 complete inclosure; a vacuum jacket or space

around said inner bottle, between said covering and said inside lining; and means for siphoning out or delivering from said inner bottle the liquid air or other liquefied gas therein as required, and for allowing the vapor 20 thereof to escape, both at varying predetermined pressures, substantially as shown and described.

Signed at New York, in the county of New York and State of New York, this 5th day of 25 February, A. D. 1902.
